UNITED STATES PATENT OFFICE.

FRED FAGG, OF CLINTON, INDIANA.

AUTOMOBILE AIR PUMP.

Application filed May 10, 1920. Serial No. 380,139.

To all whom it may concern:

Be it known that I, FRED FAGG, a citizen of the United States, residing at Clinton, in the county of Vermilion and State of Indiana, have invented new and useful Improvements in Automobile Air Pumps, of which the following is a specification.

This invention relates to air pumps, and particularly to air pumps of that type designed for use on automobiles for the purpose of supplying air for the inflation of pneumatic tires, for the operation of air-brakes, when such are used, and for other similar purposes, the primary object of the invention being to provide a compact form of air pump which may be operated by hand or by the power of the automobile motor, and which on each revolution of the pump shaft will deliver a maximum amount of air.

The invention consists of the features of construction, combination and arrangement of parts, hereinafter fully described and claimed, reference being had to the accompanying drawings, in which:

Figure 1 is a front elevation of an air pump constructed in accordance with my invention.

Figure 2 is a top plan view of the same.

Figure 3 is an end elevation of the pump.

Figure 4 is a longitudinal section through one of the cylinders, showing the associated piston, piston rod and cooperating parts.

In the practical embodiment of my invention I provide a base 1 forming a support for two opposed groups of cylinders 2 and 3 and an interposed transverse crank shaft 4, said shaft being journaled upon suitable bearing brackets 5 carried by the base. Each group of cylinders 2 and 3 comprises four cylinders, a pair of parallel short cylinders 6 and a pair of parallel longer cylinders 7, the cylinders of the pairs 6 and 7 of each group being disposed in superposed relation, a short cylinder 6 being arranged in vertical alinement with a companion long cylinder 7 of the same group.

The cylinders of each group are mounted upon a supporting stand comprising a bed plate 8 to which are suitably secured outer and inner cylinder carrying disks or heads 9 and 10, said disks or heads being fixed in any preferred manner at their lower portions to the bed plate 8 and being united at their upper portions in any suitable manner, as by means of tie rods or bolts 11. Each cylinder

has a closed outer end or head 12 and is open at its inner end, the inner ends of the cylinders of the groups 2 and 3 being arranged in opposed or facing relation. As shown, the outer end of each cylinder is threaded and fitted in a threaded opening 12' in the head 9, and the inner end of said cylinder projects through and is fitted within an opening 12" in the head 10.

Arranged within each cylinder is a piston 13, and the pistons 13 of the longitudinally aligned cylinders of each group are connected by piston rods for movement in unison, the pistons of the upper cylinders being connected by the rods 14 and the pistons of the lower cylinders by similar rods 15, the construction and arrangement being such that the pistons of the upper cylinders of the groups 2 and 3 move simultaneously in the same direction, while the pistons of the lower cylinders of the groups 2 and 3 also move simultaneously in the same direction, the said two sets of pistons however simultaneously traveling in opposite directions, as hereinafter described.

The crank shaft 4 is provided with a pair of substantially U-shaped cranks 16 and 17 arranged substantially at an angle of 90° to each other. Coupled at their inner ends to these cranks 16 and 17 are connecting rods 18 and 19. These rods are respectively coupled at their outer ends to cross heads or bars 20 and 21, the cross head 20 being pivotally connected at its ends to the upper piston rods 14, as indicated at 22, while the cross head or bar 21 is pivotally connected with the lower piston rods 15, as indicated at 23. It will thus be understood that in the revolution of the crank shaft 4 the rods 14 and 15 will be simultaneously moved in opposite directions, so that when the pistons of the upper cylinders of group 2 are on their active or compression stroke, the pistons of the upper cylinders of group 3 will be on their inactive or return stroke, and vice versa, while the converse will take place as regards the lower cylinders of the respective groups.

By the described construction and arrangement of the groups of cylinders, I am enabled to provide a pump having eight or more working cylinders in a compact group, so that a maximum amount of air may be compressed and delivered on each revolution of the crank shaft 4. As the piston rods of the similarly arranged (upper or lower) 110

cylinders of each group are coupled for operation by a single crank, and as the actuating cranks of the upper and lower cylinder rods are arranged at an angle of 90° to each other, the cross heads 20 and 21 are pivotally coupled to the sets of rods 14 and 15 equidistantly on opposite sides of the vertical line of the shaft 4, this arrangement producing a smooth and balanced operation of the working parts, whereby a compact arrangement of opposed groups each of a plurality of superposed cylinders is permitted. By this arrangement each cross head 20 and 21 has reciprocating movement mainly on one side only of the vertical line of the shaft 4, i. e., between such line and the inner ends of the cooperating cylinders on such side of the crank shaft, hence such cylinders are made comparatively short to admit of such range of movement of the cross head, while the cylinders on the opposite side of the shaft in longitudinal alinement therewith are made of greater length to provide for the requisite range of movement of the pistons therein with respect to the vertical line of the crank shaft. The two cross heads being arranged on opposite sides of the vertical line of the shaft in the manner particularly shown, the upper cylinders of group 3 and the lower cylinders of group 2 are made comparatively short, while the upper cylinders of group 2 and the lower cylinders of group 3 are made comparatively long, allowing the pistons in said cylinders to have a proper range of motion with respect to the center line of the crank shaft 4 according to the arrangement of their actuating cranks, cross heads and connecting rods.

The outer ends of the cylinders of each group are provided with air outlet or discharge pipes 24, and the pipes 24 of the upper and lower cylinders of each group are connected with each other by a branch pipe 25 and with the approximate end of a delivery pipe 26. The pipe 26 extends longitudinally of the pump and leads inwardly from the discharge outlets of the cylinder groups 2 and 3 and is provided at a suitably intermediate point with a discharge outlet 27 to which may be coupled a service pipe 28, to which a continuous stream of compressed air will be supplied from the cylinders of the groups in the operation of the pump. The service pipe 28 may be a hose pipe or other suitable pipe through which air may be supplied for inflating the pneumatic tires of the vehicle or for supplying air to a cylinder or reservoir of an air-brake mechanism, when such is used on the vehicle, or for supplying air for any other desired purpose.

The pipe 25 is provided with a check valve 25' between the outlets of the superposed sets of cylinders, to prevent the return of the air discharged from the upper pair of cylinders and the flow of air from the lower

pair of cylinders to the upper pair of cylinders, as will be readily understood.

In practice, the pump may be mounted at any suitable point upon the vehicle and the shaft 4 may be provided at one end with a gear 29 for suitable connection with the crank shaft of the engine, so that it may be operated if desired by the motive power of the vehicle, and the opposite end of the shaft may be squared or otherwise suitably formed as indicated at 30, to receive a drive crank or the like, whereby the pump may be operated by hand when desired or at times when the engine is not running.

It will, of course, be understood from the foregoing description that my invention provides a double acting pump which may be operated by rotation of the crank shaft in either direction, and that, while I have specified the pump as particularly adapted for use upon an automobile, it may be employed within a garage or service station for the purposes described and adapted to be operated by hand or power, as desired. Instead of employing a sprocket wheel upon the crank shaft for connection with a similar wheel through a drive chain upon an engine or power shaft, it will be understood that any other suitable driving connection, such as intermeshing gears or belt and pulley connections, may be employed in lieu thereof.

Having thus fully described my invention, I claim:—

In an air pump, a portable platform, cylinders grouped upon said platform at the ends thereof, the said groups each comprising two pairs of cylinders arranged parallel to each other and in superimposed relation and the cylinders of one group being axially alined with the cylinders of the other group, the upper cylinders of one set being extended inwardly beyond the inner ends of the lower cylinders and the lower cylinders of the second set being extended inwardly beyond the inner ends of the upper cylinders, a piston in each of said cylinders, piston rods extending from one group to the other and being connected to the pistons of the alined cylinders, a crank shaft mounted transversely of said platform intermediate the ends thereof and disposed equidistant between the piston rods of the upper and lower cylinders, the cranks of said shaft being disposed between the pairs of superimposed rods and said cylinders and extending at right angles to each other, bearing blocks secured to the upper and lower pairs of said rods and laterally alined with each other, bars rockably supported at their ends in said blocks, and connecting rods rigidly connected to said bars and extending longitudinally of the piston rods in opposite directions and loosely attached to the cranks of said crank shaft.

In testimony whereof I affix my signature.

FRED FAGG.
